UNITED STATES PATENT OFFICE.

MARIA CHRISTIE LLOYD, OF BELLEVILLE, NEW JERSEY.

DESIGN FOR A FLY-CATCHER.

SPECIFICATION forming part of Design No. 34,278, dated March 26, 1901.

Application filed February 6, 1901. Serial No. 46,274. Term of patent 14 years.

To all whom it may concern:

Be it known that I, MARIA CHRISTIE LLOYD, a citizen of the United States, residing at Belleville, in the county of Essex and State of New Jersey, have produced a new and original Design for a Fly-Catcher, of which the following is a specification.

This invention relates to a design for a fly-catcher, and the essential feature resides in the design as illustrated in the accompanying drawings, wherein—

Figure 1 is a perspective view of a fly-catcher embodying the feature of the design. Fig. 2 is a transverse vertical section of the same.

The design is characterized by an upper inverted frusto-conical member 1, having the upper end of an upright frusto-conical stand 2 intermediately coinciding therewith. The member 1 and stand 2 are tubular, and at the

bottom of said member is a horizontal partition 3, from which depends a tubular element 4, of cylindrical contour. The member 1 is much shorter than the stand 2 and the tubular element 4 is of such length as to have its lower end coincide with the lower end of said stand. The partition 3 completely separates the member 1 and stand 2.

Having thus described the invention, what is claimed as new is—

The design for a fly-catcher, as herein shown and described.

In testimony that I claim the foregoing as my own I have hereto affixed my signature in the presence of two witnesses.

MARIA CHRISTIE LLOYD.

Witnesses:

MARGARET DEMAREST,
NICHOLAS WHITNER.
